JOHN VAN BRUNT, OF FLUSHING, NEW YORK, ASSIGNOR TO INTERNATIONAL COMBUSTION ENGINEERING CORPORATION, OF NEW YORK, N. Y., A CORPORATION OF DELAWARE.

ASH GATE.

Application filed September 5, 1924. Serial No. 736,016.

My invention relates to gates for the discharge opening in ash-pits of furnaces, and has special reference to power operable gates for the ash-pits of automatic stokers.

5 An object of the invention is to provide a novel and improved gate of this character.

Another object of the invention is to provide a gate of this character which is of simple and durable construction, which may 10 be easily and quickly opened and closed, and which when in closed position securely seals the discharge opening in the ash-pit.

With these and other parts in view, the 15 features of the invention consist in certain constructions, arrangements and combinations of parts hereinafter described and claimed, the advantages of which will be obvious to those skilled in the art.

The several features of the invention will 20 be clearly understood from the following description and accompanying drawings, in which;

Figure 1 is a longitudinal sectional elevation of an ash-gate embodying the features 25 of the invention in their preferred form, the gate being shown associated with the discharge opening in the lower end of an ash-pit, and the section being taken on line 1—1 of Fig. 2;

Fig. 2 is an end elevation of the construction 30 illustrated in Fig. 1;

Fig. 3 is a longitudinal sectional view, partly in elevation, taken substantially on the line 3—3 of Fig. 2, showing the gate in 35 partly opened position;

Fig. 4 is a detailed sectional view taken on the line 4—4 of Fig. 3; and

Fig. 5 is a view similar to Fig. 1 but of a 40 modified form, and showing the lower end of the ash-pit in elevation.

The gate illustrated in the drawings is 45 shown associated with the lower end of an ash-pit 2 having the usual discharge opening 4 therein. As shown, a rectangular frame 6 surrounds the lower end of the wall of the discharge opening in the ash-pit, and is provided with upstanding flanges 8 embracing the inner and outer sides of the wall, the frame being provided with a depending flange 10 that defines the discharge opening 50 of the ash-pit.

In the illustrated construction the gate comprises a casting 12 having an outer up- 55 standing flange 14 and a central rib 15, the

spaces between the ribs being filled with fire 55 brick or other suitable heat insulating material 16. The gate is of suitable area so that when it is in closed position as shown in Fig. 1, it will extend over and close the discharge opening in the ash-pit, the flange 14 of the 60 gate tightly engaging the lower end of the depending flange 10 of the frame 6. The gate is mounted upon a horizontally movable carrier 16, which is adapted to be moved longitudinally to carry the gate into and out of 65 position beneath the discharge opening in the ash-pit, and means is provided for raising the gate to closed position when it has been moved beneath the discharge opening, and for lowering the gate a distance below the 70 discharge opening previously to the start of the retracting movement of the carrier.

The carrier 16 comprises a pair of longitudinally extending castings or beams 18 which are secured together by suitably arranged channel irons 20. The ends of the beams are provided with transverse bearings 22, the bearings at the corresponding ends of the beams being in alinement and receiving rock shafts 24. Each shaft 24 is further 80 supported by bearings 26 formed on brackets 28 that are secured to the adjacent channel irons 20. The shafts 24 extend beyond the bearings 22 and have flanged wheels 30 journaled on their ends. The wheels 30 ride on 85 the lower flanges of channel irons or tracks 32 that are secured on the lower end portions of suitably arranged hangers 34 having their upper ends bolted to the frame 6, a track being arranged at each side of the carrier 16. The carrier is adapted to be moved 90 back and forth longitudinally on the tracks 32 by means of a fluid operated piston rod 36 associated with the rear end thereof. The connection between the carrier and the piston rod 36 comprises a longitudinally extending bar 38, which is arranged centrally on the under side of the carrier. This bar 38 is provided with a longitudinally extending and upwardly opening inverted T-shaped 100 slot 40 which receives the lower portion of a horizontal rail 42 having its ends bolted to the under sides of the channel irons 20, said lower portion of the rail 42 corresponding in shape to the slot 40, and said bar being in sliding engagement therewith. Each 105 end of the sliding bar 38 is bifurcated and receives the lower end of a lever 44, each

lever being provided with a transverse pin 46 which is received in vertical slots 48 in the bifurcated end. The upper ends of the arms 44 are centrally secured on the rock-shafts 24 respectively. Two arms 50 are secured on each shaft 24 adjacent the outer ends of the bearings 26 of the shaft. The upper ends of the arms 50 are provided with cam rolls 52 which are adapted to engage bearing surfaces 54 on the under side of the casting 12 of the gate, each bearing surface extending between depending flanges 56 for receiving the upper end of the arm 50 between them. Hangers 58 are bolted to the under side of the casting 12 of the gate, the lower ends of which are bifurcated and extend over the shafts 24, there being two such hangers 58 associated with each shaft 24 and arranged adjacent the shaft bearings 22 on the beams 18. Each arm 50 is provided with an upstanding projection 60 which supports the gate when the latter is in the partially opened position as shown in Fig. 3, the supporting surfaces 54 resting upon the upper ends of the projections 60. The carrier bar 38 is provided with a rearward projection 62 which is connected with the piston rod 36 by a pivot pin 64. When the gate is in its advanced position as shown in both Figs. 1 and 3, a projection 66 on the forward end of the gate is in engagement with a downwardly projecting stop lug 68 on the frame 6.

With the gate in closed position as shown in Fig. 1, it is tightly held up against the flange 10 of the frame 6 by means of the cam rolls 52. When it is desired to open the gate the piston rod 36 is retracted which acts to shift the sliding bar 38 rearwardly which in turn through the depending arms 44, rocks the shafts 24 in a counter clockwise direction which swings the arms 50 downwardly and forwardly to bring their cam rolls 52 away from the supporting surfaces 54. This movement of the cam rolls 52 permits the gate 16 to be gradually lowered by gravity until it engages the upper ends of the arm projections 60 which limits its downward movement, the bifurcated ends of the guiding hangers 58 guiding the gate during this lowering movement thereof. During the continued retracting movement of the piston rod 36 the bar 38 travels with the rod and acts through the arms 44, shafts 24 and arms 50 to move the carrier 16 therewith, the arms 50 being held from further turning movement by the weight of the gate on the ends of the projections 60. The carrier is thus moved a sufficient distance to move the ash-gate out from beneath the lower end of the discharge opening of the ash-pit so as to permit the contents of the ash-pit to be discharged therefrom.

When it is desired to move the gate into closed position, the piston rod 36 is advanced

and acts through the shifting bar 38, arms 44, and rock-shafts 24 to move the carrier and the gate therewith, the weight of the gate on the upward projections 60 holding the rock-shafts 24 from turning movement at this time. This advancing movement of the gate continues until the projection 66 on the forward end thereof engages the stop lug 68 which arrests the movement of the gate so as to position it directly beneath the discharge opening of the ash-pit. During the continued advancing movement of the piston rod 36 after engagement of the projection 66 with the stop 68, the shifting bar 38 acts through the arms 44 and rock-shafts 24 to swing the cam roll arms 50 upwardly, which causes the cam rolls 52 to act on the bearing surfaces 54 to force the ash-gate upwardly against the flange 10 of the discharge opening of the ash-pit, so as to tightly and firmly close the opening. The ash-gate is held in closed position by the cam rolls 52, the axes of which are positioned directly above the axes of the shafts 24.

It will be apparent with this construction, whereby the ash-gate in opening is first dropped a distance below the discharge opening before it is moved from beneath the discharge opening, and in closing is first returned to said position below the discharge opening before it is brought against the lower end of the opening, that the opening and closing of the gate is easily accomplished without danger of interference from ashes in the ash-pit, and the ash-gate when in closed position tightly and firmly seals the discharge opening.

In the modified construction illustrated in Fig. 5, instead of the raising and lowering of the gate being accomplished by means of the cam rolls 52, such movement is effected by means of arms 70 having their lower ends secured to the rock-shafts 24 and their upper ends pivotally connected with pivot pins 72 secured in depending ears 74 on the under side of the gate. With this construction, at the start of the retracting movement of the piston rod 36 to open the gate, the rock-shafts 24 during their turning movement in a counter clockwise direction swing the ends of the arms 70 downwardly and thus lower the gate preliminary to the continued retracting movement of the piston rod 36 to move the gate carrier and gate from beneath the discharge opening of the ash-pit. On engagement of the projection 66 with the stop lug 68 near the limit of the advancing movement of the piston rod 36 to move the gate into closed position, the shifting bar 38 acts through the depending arms 44 on the rock-shafts 24 to turn the rock-shafts in a clockwise direction and thus act through the arms 70 to force the gate up against the flange 10 of the discharge opening of the ash-pit, the gate being held in closed posi-

tion at the completion of this movement by the axes of the pivotal connections between the arms 70 and the ears 74 on the gate being positioned directly above the axes of the 5 rock-shafts 24.

As will be evident to those skilled in the art, my invention permits various modifications without departing from the spirit thereof or the scope of the appended claims.

10. What I claim is:

1. The combination of an ash pit having a discharge opening, and means for closing said opening comprising a gate, a carrier for moving the gate into and out of position beneath said opening, a stop for limiting said inward movement of the carrier, and means acting automatically upon the carrier reaching the limit of said movement to raise said gate with relation to the carrier toward said 20 opening.

2. The combination of an ash-pit having a discharge opening, and means for closing said opening comprising a gate, a frame surrounding the lower end of the wall of said 25 opening having a depending stop member, means for moving the gate beneath said opening and against said stop member, and means acting automatically upon engagement of the gate with the stop member for 30 effecting the raising of the gate towards said frame.

3. The combination of an ash-pit having a discharge opening, and means for closing said opening comprising a gate, a carrier 35 therefor movable horizontally to move the gate into and out of position beneath said opening, arms pivotally mounted on the carrier beneath the ends, respectively, of said gate and acting when turned simultaneously 40 in one direction to raise said gate, and means for thus turning said arms.

4. The combination of an ash-pit having a discharge opening, and means for closing said opening comprising a gate, a carrier 45 therefor movable horizontally to move the gate into and out of position beneath said opening, levers pivotally mounted on the carrier beneath the ends, respectively, of said gate and acting when turned simultaneously 50 in one direction to raise said gate, and means comprising a horizontally movable bar connecting said levers for thus turning them.

5. The combination of an ash-pit having 55 a discharge opening in its lower end, and means for closing said opening comprising a gate, a carrier therefor, movable in opposite directions to move the gate into and out of position beneath said opening, means for 60 raising said gate towards said opening when it is moved into position beneath said opening, comprising arms pivotally mounted on

the carrier beneath the ends, respectively of the gate, cam rolls mounted on the upper ends of said arms and adapted to act on the 65 under side of the gate to raise the gate upon turning movement of the arms in one direction, and means for thus turning said arms.

6. The combination of an ash-pit having a discharge opening, and means for closing 70 said opening comprising a gate, a carrier therefor movable horizontally to move the gate into and out of position beneath said opening, a bar mounted for limited longitudinal movement on the carrier, connections between the bar and carrier for moving the carrier in one direction to move the gate into position beneath said opening and connections between the bar and gate acting automatically for raising the gate toward said 80 opening upon said gate being moved into position beneath said opening.

7. The combination of an ash pit having a discharge opening, and means for closing said opening comprising a gate, a carrier for 85 moving the gate into and out of position beneath said opening, a stop adapted to be engaged by the gate to limit said movement of the gate and carrier, and means acting automatically upon engagement of the gate 90 with said stop to raise said gate with relation to the carrier toward said opening.

8. The combination of an ash pit having a discharge opening and means for closing said opening comprising a gate, means for 95 moving the gate into and out of position beneath said opening, a stop for limiting the inward movement of the gate, and means acting automatically upon the gate reaching the limit of its inward movement to raise 100 said gate toward said opening.

9. The combination of an ash pit having a discharge opening, and means for closing said opening comprising a gate, means for moving the gate into and out of position beneath said opening, a combined stop and guiding member for the gate for limiting the inward movement of the gate and for guiding the gate while it is being raised toward said opening, and means acting automatically upon the gate reaching said limit of its inward movement to raise it toward 105 said opening. 110

10. The combination of an ash pit having a discharge opening, and means for closing 115 said opening comprising a gate, a carrier therefor to move the gate into and out of a definite position beneath said opening, said gate extending directly over the top of said carrier, and means acting automatically upon the gate reaching said definite position beneath said opening to raise it with relation to the carrier toward said opening. 120

JOHN VAN BRUNT.
